United States Patent

Des. 236,894
Patented Sept. 23, 1975

236,894

FAUCET HANDLE

Ronald J. Rice, 241 Overton Place,
Oakville, Ontario, Canada

Filed Feb. 22, 1973, Ser. No. 334,636

Term of patent 14 years

Int. Cl. D23—01

U.S. Cl. D23—28

FIG. 1

FIG. 2

FIG. 3

FIG. 1 is a top view of a faucet handle, showing my new design,

FIG. 2 is a side elevational view thereof, and

FIG. 3 is a bottom view thereof.

In the drawings the oblique line, stippled and parallel line shadings are to indicate contrasting materials.

I claim:

The ornamental design for a faucet handle, as shown as described.
